UNITED STATES PATENT OFFICE.

GEORGE E. BROWN, OF BOSTON, MASSACHUSETTS.

HORSESHOE.

SPECIFICATION forming part of Letters Patent No. 259,630, dated June 13, 1882.

Application filed January 24, 1880.

To all whom it may concern:

Be it known that I, GEORGE E. BROWN, of Boston, in the county of Suffolk and State of Massachusetts, have invented a new and useful Horseshoe, of which the following is a specification.

My invention relates to improvements in horseshoes, in which the sides are gradually increased in thickness vertically as they approach the heels, with an outward bevel to their upper surfaces; and the objects of my improvements are, first, to provide a means in a horseshoe for spreading a contracted hoof; second, to afford facilities for raising the heel 15 for forcing the bones of the ankle back between the walls of the foot at the heel. These objects I attain by the mechanism illustrated in the accompanying drawings, in which—

Figure 1 represents a perspective view of 20 the entire device. Fig. 2 is a top or plan view of the same, and Fig. 3 is a cross-section taken at the line X X of Fig. 2.

Similar letters refer to like parts in the several views.

25 A represents the front part of the shoe, which is forged down thin and the surplus metal drawn back into each side B B of the shoe. These sides B B gradually increase in thickness vertically but decrease in thickness laterally as they approach the heel ends. The lower surface of the shoe is perfectly flat and level, and the upper surface gradually increases in thickness from the toe to the extreme ends of the heels. At the same time the 30 upper surface of each heel C C is beveled with an incline outward, as shown in the cross-

section of Fig. 3, and the inner portion of the upper surface of the shoe is beveled inward, as shown at b b in Figs. 1 and 2.

The amount of metal above the line f shows 40 the added thickness of metal in my improved shoe from that of the ordinary shoe.

The nail-holes are perforated in the shoe nearer to the toe on each side than in the ordinary shoes, thus leaving the rear portion of 45 the hoof on each side of the shoe free to be expanded by the outward bevel or inclination given to the upper surface of the heels C C.

I am aware that prior to my invention horseshoes have been made with an increased thickness of the sides toward the heels; also, that 50 shoes have been made with the heels split by horizontal slots, forming spring-heels, and to such devices I make no broad claim; but

What I do claim as my invention, and desire 55 to secure by Letters Patent, is—

The new article of manufacture, consisting of a horseshoe having a flat bearing-surface from the toe to the quarters, the sides gradually increasing in thickness vertically, but diminishing in thickness laterally, and having 60 their upper parts inclined outwardly from the quarters to the heel and the inner upper surface concaved, as shown and described.

In testimony whereof I have signed my name 65 to this specification in the presence of two subscribing witnesses.

GEO. E. BROWN.
